Patented Mar. 22, 1887.

UNITED STATES PATENT OFFICE.

LEWIS D. CORTRIGHT, OF HYDE PARK, ILLINOIS, AND STEPHEN P. DARLINGTON, OF WEST CHESTER, PENNSYLVANIA, ASSIGNORS TO THE CORTRIGHT METAL ROOFING COMPANY, OF PENNSYLVANIA.

METALLIC ROOFING-PLATE OR SHINGLE.

SPECIFICATION forming part of Letters Patent No. 359,958, dated March 22, 1887.

Application filed January 3, 1887. Serial No. 223,164. (No model.)

To all whom it may concern:

Be it known that we, LEWIS D. CORTRIGHT, of Hyde Park, Cook county, Illinois, and STEPHEN P. DARLINGTON, of West Chester, county 5 of Chester, and State of Pennsylvania, have invented a new and useful Improvement in Metallic Roofing-Plates or Shingles, of which the following is a true and exact description, due reference being had to the accompanying 10 drawings, which form a part hereof.

Our improvement has especial reference to roofing-plates of the kind which are adapted to be secured to the roof by beginning to lay them at the comb and working downward to the eaves; and the object of our invention is to 15 make such shingles more thoroughly watertight than has heretofore been the case, and guard against the danger of the water getting through the metallic sheathing. Some of our 20 improvements are, however, also capable of useful application with metal shingles of the ordinary types, which are secured to the roof, beginning at the eaves and continued in overlapping layers to the comb.

Reference being now had to the drawings which illustrate our improvements, Figure 1 is a plan view of four of our improved shingles interlocked together as they are secured upon the roof; Fig. 2, a section through the 25 lower corner of one of our shingles on the line $z z$ of Fig. 1; Fig. 3, a cross-section of one of the shingles on the line $y y$ of Fig. 1; Fig. 4, a cross-section of the joint of two interlocked shingles, taken, for instance, on the line $x x$ of Fig. 1; Fig. 5, a cross-section of the joint of two shingles situated one vertically over the other, as on the line $w w$ of Fig. 1. Fig. 6 is a back view of one of our improved shingles. Fig. 7 is a perspective view of three shingles 30 grouped as in Fig. 1, with the upper one removed. Figs. 8 and 9 are cuts of the blanks out of which our improved shingles are made, and Fig. 10 is a view similar to Fig. 1, showing another way in which the shingles can be 35 interlocked and secured upon the roof.

A, B, C, and D are four of our improved metallic shingles constructed in what we believe to be their best form.

E E are the two upper edges of the shingles, in which is formed the depressed gutter E', 50 E² being the extreme outer edge of the sheet formed into a downwardly-bent flange extending obliquely from the top of the gutter down toward the plane of its bottom.

e is the extreme top of the shingle, where 55 the gutters E' E' run into each other, and which we prefer to cut off in a horizontal line, as shown, for reasons hereinafter explained.

F F are the two lower edges of our shingles. They are bent so as to form the fold f and nail-flange F', the edge of the fold being also 60 bent over to form the hook-like edge F'. The depth of the fold f should be such as to enable it to contain the whole of the gutter E', as is shown in Fig. 4.

a is the lower vertical point of our shingle, the blank from which the shingle is formed being so cut at this point that the metal bent back to form the folds f on the two adjacent edges shall not interfere or lap the one upon 70 the other.

We prefer to cut the metal blank as shown in Figs. 8 and 9, a piece, G, being cut out of the lower corner, the length of the horizontal cut $g' g'$ in said piece being substantially equal 75 to the distance between the corners $a' a'$ when folded, as shown in Fig. 6. When so cut, the piece G may be applied to the lower corner of the shingle, as shown, its arms $g^2 g^2$ being inserted in the folds f, as shown in Fig. 6, and 80 its horizontal edge $g' g'$ being preferably bent up and soldered to the shingle, as shown in Fig. 5. The lateral corners $f' f'$ of the blank are preferably cut away, as shown, so that the fold f shall not extend under the depressed gutter E', and, as we have already mentioned, the top corner of the shingle should also be cut away in a horizontal line, as shown at e.

The mode of construction and application of our shingles will be readily understood. 90 A blank being prepared substantially as shown in Figs. 8 and 9, the edges E E are bent or stamped so as to form in them the gutters E' and flange E². The edges F F are also bent to form the fold f, with its depressed edge F' 95 and nailing-flange F', either of these opera-

tions being performed first, or even both at the same time. The edge $g'g'$ of the piece G having been bent upward, its arms g^2g^2 are then inserted in the folds $f'f$ and the edge $g'g'$ soldered to the bottom of the shingle, the bottom corner of which, when finished, is best shown in Figs. 2 and 6.

In applying these shingles to a roof they should be laid from the top or comb downward in horizontal layers or rows, and preferably slightly staggered, as shown in Fig. 1; although their edges may be made to register, as in Fig. 10, if desired. The edges E E of each shingle are thrust into the flanges $f'f$ of the two adjoining shingles in the row above, the function of the obliquely-inclined flanges E² being to facilitate the entrance of the edges E under the downwardly-bent edges F' of the fold f, and the sides of the gutters E' are made with a divergent incline, as shown, so that the edge F' of the fold may slide up out of the gutter and rest on the surface of the lower shingle when it is pushed home, as shown in Fig. 4, the natural spring of the metal causing the edge F' to form a close and tight contact with the surface of the shingle upon which it rests. In forcing the lower shingle into place its upper corner, e, passes under the lower corner, a, of the shingle vertically above it and over the piece G, when it is used, the horizontal edge of the corner e registering or nearly registering with the horizontal line between the corners a' a' of the shingle above when the shingles are staggered.

At each corner the lower point, a, of a shingle is raised from the roof by the thickness of the shingle immediately below it and that of the lateral shingles, which are thrust between the lower and upper shingles at the corners. The point a would therefore naturally be separated from the shingle below by a distance equal to the thickness of the edges of the lateral plates; but this distance we diminish by bending down the points a, as shown in Fig. 5. As will be seen, we secure by our construction a tight joint between the edges F' of the upper shingles and the surface of the lower ones, and avoid the continued contact or close approach of the metal edges and folds forming the joints, thus avoiding the capillary action, which has been found to have a strong tendency to cause such joints to leak. Any water passing beyond this joint is caught in the gutters E', which lead it onto the surfaces of the lower shingles, (see Fig. 7,) and if, by reason of capillarity or other cause, any of the water escaping from the gutters should work upward on the shingle on which it empties, it is intercepted by the gutters on its upper edges, which gutters may be said to be interlocked with the gutters of the upper shingles.

We consider the piece G as a convenient addition to our shingle, but it is not essential, and even when used need not necessarily be soldered at g, as shown. The form of the blank may also be changed at any or all of its corners in many ways. Thus, if the shingles are not to

be staggered, it is not necessary to cut off the upper corner, e, the cuts in the corners f' f', may be made deeper and need not necessarily be square, and the main requisite in the cutting of the lower corner, a, is that the folded sides F should not lap over each other. Our improved gutter and fold may also be used with advantage for vertical seams, in which use the oblique flange E² may be dispensed with, though we would recommend its use. We also believe that our device of a depressed gutter will be found useful even where the fold f or other projecting edge of another shingle is not provided with a downwardly-bent edge, F', though we prefer to use it in this connection.

The feature of the downwardly-bent edge F' on a fold, such as f, is also capable of useful application even when the corresponding flange to be inserted in it has a gutter formed in any usual way, and even when no gutter at all is used within the seam. In all cases the edge F' should of course press against the inserted shingle.

Having now described our invention, what we claim, and desire to secure by Letters Patent, is—

1. In metal shingles adapted to interlock with each other, the combination of an edge, F, having a fold, f, with downwardly-bent edge F', and nailing-flange F², with an edge, E, having a depressed gutter, E', with a sloping inward edge.
2. In metal shingles adapted to interlock with each other, the combination of an edge, F, having a fold, f, with downwardly-bent edge F', and nailing-flange F², with an edge, E, having a depressed gutter, E', with a sloping inward edge and an obliquely-inclined flange, E².
3. In metal shingles adapted to interlock with each other, the combination of the adjoining edges F, having folds f, with downwardly-bent edges F', and nailing-flanges F², with the opposite adjoining edges E, having depressed gutter E', and inclined flanges E².
4. In metal shingles adapted to interlock with each other, the combination of the adjoining edges F, having folds f, with downwardly-bent edges F', and nailing-flanges F², with the opposite adjoining edges E, having depressed gutters E', with inclined inner sides and inclined flanges E².
5. In metal shingles adapted to interlock with each other, substantially as shown and described, the combination, with the main shingle, of the plate G, as and for the purpose specified.
6. In metal shingles adapted to interlock with each other, substantially as shown and described, the corner a, cut and bent substantially as shown, so that the shingles may be staggered or set in broken lines upon the roof.
7. In metal shingles adapted to interlock with each other, substantially as shown and described, the corner e, cut horizontally, so that the shingles may be staggered or set in broken lines upon the roof.

8. In metal shingles adapted to interlock with each other, substantially as shown and described, the corners $f' f'$, cut so that the folds f shall terminate just before the points 5 where the gutters E' cross the lateral corners of the shingles.
9. In a metallic shingle, the device of a gutter depressed below the level of the sheet formed in the edge or edges of the same and adapted to be covered in use by a flange or projection of another shingle.
10. In metallic shingles adapted to interlock with each other, substantially as specified, the combination of depressed gutters formed in

the upper edges thereof, with overlapping 15 flanges formed in the lower edges thereof and continued to form nailing-flanges.

11. In a metallic shingle, the device of an S-shaped flange, f , continued to form a nailing-flange, having a downwardly-projecting 20 edge, F' , adapted to rest upon the surface of a shingle inserted in said flange.
